CLAIM

The ornamental design for an electrical connector, as shown and described.

DESCRIPTION

This application is related by subject matter to U.S. Design patent No. D616,827 issued Jun. 1, 2010.

FIG. 1 is a top, right, front perspective view of an electrical connector according to our design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken line portion of the figure drawings is included to show unclaimed subject matter only and forms no part of the claimed design.

In a preferred embodiment, the nature of this product is an electrical connector in the form of an electrical connector housing configured for retaining a plurality of electrical contacts.
